WARREN G. KELLOW, OF LOS ANGELES, CALIFORNIA.

TLTING MECHANISM FOR DOLLS' EYES.

1,404,970.

Specification of Letters Patent.

Patented Jan. 31, 1922.

Application filed March 22, 1919. Serial No. 284,444.

To all whom it may concern:

Be it known that I, WARREN G. KELLOW, a citizen of the United States, residing at Los Angeles, in the county of Los Angeles and State of California, have invented new and useful Improvements in Tilting Mechanisms for Dolls' Eyes, of which the following is a specification.

My invention relates more particularly to improvements in that class of dolls' eye tilting mechanisms as shown and described in my allowed application entitled "Adjustable eye tilting device for dolls," Serial No. 249,511, filed Aug. 12, 1918, and refers more especially to improvements on that construction.

In the construction above referred to when the doll was slightly inclined from a vertical position, the eye tilting mechanism immediately started a tilting operation, thereby causing the doll's eyes to partially close which has been found to be objectionable as children do not wish to have the doll's eyes partially closed when carrying the same in their arms. By means of my improved construction the eye tilting mechanism will not operate until the doll has assumed a greatly inclined position from the vertical, thus allowing a slight inclination of the doll on a movement from a vertical to a horizontal position without in the least affecting an operation of the eye tilting mechanism.

Again no provision was made in my first construction to prevent a contact of the gravity weighted arm against the interior of the doll's head when the same was raised from a horizontal position to a vertical one, the noise caused by such contact being an objectionable one. By means of my improved construction all noises attendant upon an operation of the eye tilting mechanism is eliminated.

A main object of my invention is to provide a dolls' eye tilting mechanism, that will not operate to cause a complete closing movement of the doll's eyes until the doll is nearly brought into a horizontal position.

A further object is to provide an eye tilting mechanism which is silent in operation. I accomplish the above objects by means of the mechanism herein described and illustrated in the accompanying drawing in which:

Fig. 1 is a rear elevation of the front half

of a doll's head showing my improved eye 55 tilting mechanism mounted therein.

Fig. 2 is a longitudinal section of a doll's head taken on line 2—2 of Fig. 1, the doll's head being in a vertical position.

Fig. 3 is a detail cross section taken on 60 line 3—3 of Fig. 1.

Fig. 4 is a view similar to Fig. 2, illustrating the degree of inclination from the vertical necessary to cause an eye tilting movement.

Referring now more especially to the drawings, 5 indicates the front portion of a doll's head which is usually formed of a plastic composition, the rear portion of the head not being illustrated as it forms no part 70 of my invention. The doll's head is provided in the front thereof with the usual eye socket openings 6 back in which are mounted the movable eyes.

The eye tilting device, as in my former 75 patent, preferably consists of a stamped metallic member, comprising transversely extending slotted arms 7 and 8, each arm being provided on its outer end with a pivotal bearing point 9. Horizontal arms 7 80 and 8 are provided with a longitudinally extending slot 10 through which pass tacks or other securing means 11 by means of which the eyes are adjustably secured to the arms as will be more particularly described here- 85 inafter. The pivotal bearing points 9 of the arms 7 and 8 engage the interior surface of the doll's head adjacent the eyes, as clearly shown in Figs. 1 and 3 of the drawing, being held in position by means of a plastic 90 substance 12 to prevent the accidental displacement of the bearing points 9 when in position in the doll's head.

The doll's eyes 15 are preferably formed of wood or a similar material and are hemispherical in form as clearly shown in various views of the drawing, the hemispherical portion having a thin covering formed of celluloid 16, the outer surface of which presents a simulation of the human eye. Each of eyes 100 15 on their flat sides are preferably provided with centrally disposed indentations 17 which are engaged by the tacks 11 when the eyes are adjustably secured to the slotted arms 7 and 8 of the tilting mechanism. 105

Extending upwardly from the upper edge of arms 7 and 8, and midway between their ends, is arm 18 designed to limit the move-

ment of the tilting device and the eyes connected thereto so that when the doll is brought into a reclining or horizontal position, the doll's eyes will have the appearance of being closed, as in sleep.

Formed integral with arm 7 and 8 and depending therefrom and also in vertical alinement with arm 18 is an actuating arm 19, said arm being provided on its lower end 10 with a gravity weight 20 which serves to operate the tilting device to bring the eyes into an open or closed position when desired. Arm 19 is preferably provided on its outer face with a spring arm 21, the lower end of 15 the arm preferably being formed integral with arm 19 but it may be formed separate if desired and attached to the weight 20 in a desired manner. Arm 21 extends upwardly and is turned into a hooked form as 20 clearly shown in Fig. 2 of the drawing so that its end 22 will contact with the interior surface of the doll's head. By means of arm 21 the tilting mechanism will be limited in its forward movement when the doll is 25 brought from a reclining or horizontal position into a vertical one, as shown. Also by means of said arm all noise which is usually occasioned by the weighted arm striking the interior of the doll's head will be eliminated, the arm 21 preventing an engagement 30 of the gravity weight 20 with the head portion.

In adjusting the tilting mechanism the arm 19 is bent inwardly and the hooked end 35 22 of arm 21 is adjusted so that the gravity weight 20 is greatly to the rear of the doll's eyes, thus permitting the doll to be greatly inclined from its vertical position without an actuation of the tilting mechanism.

40 It will also be observed that by means of this construction the doll itself must be inclined from its vertical axis as clearly illustrated in Fig. 4 of the drawing before the weighted arm will begin to actuate the tilting mechanism, the full closing of the eyes not occurring until the doll has almost reached a horizontal position.

From the foregoing description it will be apparent that a child may carry a doll 50 provided with my eye tilting mechanism slightly out of its vertical position in her arms without causing a movement of the eyes which is found to be highly desirable.

What I claim is:

55 1. In combination with a doll's head hav-

ing eye openings therein, of an eye tilting mechanism pivotally mounted within said head, a pair of eyes carried by said mechanism and registering with the eye openings of the doll's head, a weighted arm connected to said tilting mechanism for actuating the same on a movement of the doll from one position to another, and means to adjust said actuating arm, whereby to prevent a movement of said arm until a desired inclination of the doll has been reached on its movement from a vertical to a horizontal position.

2. In combination with a doll's head having eye openings therein of an eye tilting device pivotally mounted therein, having a pair of eyes mounted thereon and registering with said eye openings formed in the doll's head, a weighted arm carried by said device for actuating the same on a movement of the doll from one position to another, and an arm connected to said weighted arm, said arm adapted to prevent a tilting movement of said tilting device during a movement of the doll from a vertical to a horizontal position until a desired inclination has been reached in its movement.

3. In combination with a doll's head having eye openings therein, of an eye tilting device having a pair of eyes secured thereto pivotally mounted within said doll's head, said eyes registering with the openings formed in the doll's head, a weighted actuating arm connected to said device, and adjustable means secured to the actuating arm adjacent the weighted end thereof for limiting the movement of the actuating arm in one of its movable directions.

4. In combination with a doll's head having eye openings therein, of an eye tilting device pivotally mounted within said head, a weighted arm connected to said device for actuating the same on a movement of the doll from one position to another, and a spring arm connected to the lower end of 95 said weighted arm adapted to contact with the interior of the doll's head on a movement of said doll from a horizontal to a vertical position, whereby to cause a silent operation of the tilting device.

In witness that I claim the foregoing I have hereunto subscribed my name this 10th day of March, 1919.

WARREN G. KELLOW.
